The ornamental design for a suction adapter, as shown and described.

DESCRIPTION

FIG. 1 is a perspective view of one embodiment of a suction adapter.

FIG. 2 is a top plan view of the suction adapter of FIG. 1.

FIG. 3 is a bottom view of the suction adapter of FIG. 1.

FIG. 4 is a front view of the suction adapter of FIG. 1.

FIG. 5 is a rear view of the suction adapter of FIG. 1.

FIG. 6 is a right side view of the suction adapter of FIG. 1.

FIG. 7 is a left side view of the suction adapter of FIG. 1.

FIG. 8 is an enlarged fragmentary perspective view of portion 8 of the suction adapter of FIG. 1.

FIG. 9 is an enlarged fragmentary perspective view of portion 9 of the suction adapter of FIG. 1.

FIG. 10 is a perspective view of another embodiment of a suction adapter.

FIG. 11 is a top plan view of the suction adapter of FIG. 10.

FIG. 12 is a bottom view of the suction adapter of FIG. 10.

FIG. 13 is a front view of the suction adapter of FIG. 10.

FIG. 14 is a rear view of the suction adapter of FIG. 10.

FIG. 15 is a right side view of the suction adapter of FIG. 10.

FIG. 16 is a left side view of the suction adapter of FIG. 10.

FIG. 17 is an enlarged fragmentary perspective view of portion 17 of the suction adapter of FIG. 10; and,

FIG. 18 is an enlarged fragmentary perspective view of portion 18 of the suction adapter of FIG. 10.

The broken lines shown in the figures represent portions of the suction adapter that form no part of the claimed design.
